(57) **CLAIM**

The ornamental design of a clock, as shown and described.

DESCRIPTION

FIG. 1 is a front perspective view of my new design.

FIG. 2 is a top plan view thereof.

FIG. 3 is a bottom plan view thereof;

FIG. 4 is a front elevation view thereof.

FIG. 5 is a rear elevation view thereof.

FIG. 6 is a right side elevation view thereof;

FIG. 7 is a left side elevation view thereof.

FIG. 8 is another front perspective view thereof in an alternate environment; and,

FIG. 9 is a front elevational view of FIG. 8.

The broken-lines showings of FIGS. 1-9 are for illustrative purposes only and form no part of the claimed design. Specifically, those of FIGS. 1-7 show the design with suction legs, while those of FIGS. 8 and 9 show the design with magnetic legs.
